CLAIM

The ornamental design for a dental buccal tube, as shown and described.

DESCRIPTION

FIG. 1 is a front right perspective view of a dental buccal tube;

FIG. 2 is a front view of the dental buccal tube according to the embodiment of FIG. 1;

FIG. 3 is a rear view of the dental buccal tube according to the embodiment of FIG. 1 of the dental buccal tube according to the embodiment of FIG. 1;

FIG. 4 is a left side view of the dental buccal tube according to the embodiment of FIG. 1;

FIG. 5 is a right side view of the dental buccal tube according to the embodiment of FIG. 1;

FIG. 6 is a top view of the dental buccal tube according to the embodiment of FIG. 1;

FIG. 7 is a bottom view of the dental buccal tube according to the embodiment of FIG. 1;

FIG. 8 is a front right perspective view of the dental buccal tube according to the embodiment of FIG. 1, in the change state;

FIG. 9 is a front view of the dental buccal tube according to the embodiment of FIG. 1, in the change state;

FIG. 10 is a rear view of the dental buccal tube according to the embodiment of FIG. 1, in the change state;

FIG. 11 is a left side view of the dental buccal tube according to the embodiment of FIG. 1, in the change state;

FIG. 12 is a right side view of the dental buccal tube according to the embodiment of FIG. 1, in the change state;

FIG. 13 is a top view of the dental buccal tube according to the embodiment of FIG. 1, in the change state; and,

FIG. 14 is a bottom view of the dental buccal tube according to the embodiment of FIG. 1, in the change state.

The dental buccal tube may be used for orthodontic treatment, while the concealable traction hook can be stored and unfolded according to the treatment needs.

The broken lines immediately adjacent the shaded areas represent the bounds of the claimed design while all other

(Continued)

broken lines are for the purpose of illustrating portions of the dental buccal tube; the broken lines form no part of the claimed design.
